UNITED STATES PATENT OFFICE

ANTONE C. COLOSIMO, OF SAN FRANCISCO, CALIFORNIA

TANK FILLING DEVICE

Application filed October 14, 1929. Serial No. 399,591.

This invention relates to improvements in tank filling devices and has particular reference to means for filling gasoline tanks such as automobile tanks and the like.

5 The principal object of the invention is to provide a device wherein the ordinary gasoline pump filling hose may be securely attached to the filling cap of the tank.

10 A further object is to provide means whereby spilling of the gasoline will be eliminated.

A further object is to produce a device whereby the confined air within the tank may escape.

15 A still further object is to provide a quick detachable means thereby saving delays in filling.

Other objects and advantages will be apparent during the course of the following 20 description.

In the accompanying drawings forming a part of this specification and in which like numerals are employed to designate like parts throughout the same,

25 Figure 1 is an end elevation of the tank having my improved cap and hose connection attached thereto,

Figure 2 is a view similar to Figure 1 showing the manner in which my hose connection can be employed without the use of the cap on old styled tanks,

30 Figure 3 is a side elevation of my cap and hose connection in separated position,

Figure 4 is a cross sectional view taken on 35 the line 4-4 of Figure 5 and showing the interior mechanism of my device,

Figure 5 is a cross sectional view taken on the line 5-5 of Figure 4, looking in the direction of the arrow, and

40 Figure 6 is a cross sectional view taken on the line 6-6 of Figure 4.

In the filling of gasoline tanks on motor vehicles, it is common to remove the cap from the top of the tank and then to insert a hose into the tank through which the gasoline flows through the pump. It often occurs that the hose will slip and consequently a large amount of gasoline is spilled, which means a loss and also increases the fire hazard. With my device a peculiarly arranged

cap is secured to the tank and becomes a permanent fixture thereon, to which the hose is connected through the medium of a bayonet connection.

In the accompanying drawings wherein for the purpose of illustration is shown a preferred embodiment of my invention, the numeral 5 designates any standard tank having a customary threaded nipple 6 to which it is common to secure the cap. Instead of employing an ordinary cap, I employ a peculiarly shaped cap 7 having a threaded portion 8 which engages the nipple 6. This cap is provided with a reduced portion 9 which is interiorly threaded as at 9. An inlet opening is shown at 11 which communicates with a chamber 12 in which is placed a ball 13 held against a seat 14 by a spring 16. This seat is formed in a tubular member 17 which is threaded so as to engage the threads 9 and has a reduced end 18 projecting from which are pins 19. These pins are adapted to enter bayonet slots 21 formed in a connection 22 secured to a coupling member 23. This coupling member is tubular in form and has a chamber 24 adapted to house a spring 26 which presses against a packing 28 and against the head 29 of a tubular element 31 to which the filling hose 32 is attached. At 33 I have shown a bleeder tube in which a ball check 34 is positioned.

In operation, my cap is attached to a tank and the hose is connected to the pipe 31. By now bringing the two together so that the pins 19 enter the bayonet slots 21 it will be evident that the member 18 will be brought into contact with the packing 28 thus effecting a seal between the two parts. As the gasoline flows as indicated in the tailed arrows, the same will enter pass the ball check and into the tank while the air within the tank will pass out through the bleeder as indicated in the plain arrows.

It is to be understood that the form of my invention herewith shown and described is to be taken as a preferred example of the same, and that various changes relative to the material, size, shape and arrangement of parts may be resorted to without departing

from the spirit of the invention or the scope of the subjoined claim.

Having thus described my invention, I claim:—

- 5 In a device of the character described the combination with a gas tank and a hose for filling the tank, of a filler cap having an open end adapted to be secured to the tank and provided with an opposite walled end
- 10 having an upper and lower vent opening therein, a relief valve secured to the walled end adjacent the upper vent opening, a valve housing secured to the walled end adjacent the lower vent opening and communicating therethru with the filler cap, a coupling element for retaining the hose, and cooperating means carried by said valve housing and coupling for removably securing the coupling to said housing.
- 15

20 In testimony whereof I affix my signature.
ANTONE C. COLOSIMO.
